UNITED STATES PATENT OFFICE.

GEORGE A. KLEINOW, OF NORTH McGREGOR, IOWA.

PUMP DRIVE-GEARING.

1,115,837.

Specification of Letters Patent.

Patented Nov. 3, 1914.

Application filed March 27, 1914. Serial No. 827,632.

To all whom it may concern:

Be it known that I, GEORGE A. KLEINOW, a citizen of the United States, residing at North McGregor, in the county of Clayton 5 and State of Iowa, have invented a new and useful Pump Drive-Gearing; and I do hereby declare the following to be a full, clear, and exact description of the invention, such as will enable others skilled in the art to 10 which it appertains to make and use the same.

This invention relates to a new and useful improved pump drive gearing, and one in which friction is reduced to a minimum.

15 An object of the invention is to provide an improved gearing of this nature, so connected between the windmill rod and the pump rod, that the pump rod will operate at a greater rate of speed than the windmill 20 rod, say for instance, substantially twice as fast.

One of the features of the invention is the provision of an improved guide frame, in which the gearing is mounted, there being 25 a rack frame also mounted in the guide frame, and guided thereby.

Another feature of the invention is the provision of a large gear engaging the teeth of one side of the rack frame, and having a 30 smaller segmental gear arranged concentrically with the larger gear, said segmental gear being in mesh with a pinion, which meshes with and operates the pump rod.

In practical fields the details of construction may necessitate alterations, falling 35 within the scope of what is claimed.

The invention comprises further features and combination of parts, as hereinafter set forth, shown in the drawings and 40 claimed.

In the drawings:—Figure 1 is a view in elevation, showing the improved drive gearing operating in conjunction with the windmill rod and the pump rod, showing the 45 windmill rod at its limit on its upward stroke, and the pump rod at its limit on its upward stroke, showing the relative positions of the two. Fig. 2 is a view similar to Fig. 1 illustrating the difference between 50 the relative movements of said windmill and pump rods. Fig. 3 is a sectional view on line 3—3 of Fig. 1. Fig. 4 is a sectional view on line 4—4 of Fig. 1.

Referring more especially to the drawings 55 1 designates the windmill rod having a pitman 2 connected thereto, and which pitman

is in turn pivoted at 3 to the rack frame 4. This rack frame is elongated in contour and comprises the side bars 5 and 6, the bar 6 being provided with laterally extending end parts 7 and 8, which are connected adjustably to the side bar 5. This adjustable connection comprises the several notches 9, any one of which in each of said end parts 7 and 8 is designed to engage the bolt 10, 65 and by screwing up the winged nut 11, the adjustable connection is made secure. The side bar 5 is provided with teeth 11, thereby constituting a side rack bar, the teeth of which engage the teeth of the gear 70 rim 12. Arranged concentric with an integral web of the gear rim 12 is an inner gear rim 16 having gear teeth 15 meshing with the pinion 14, with the shaft of which the pinion 34' rotates. The two rims 12 and 16 are connected together by the spokes 75. The inner rim 16 has spoke connections with the bearing sleeve 18, which is mounted upon a stub shaft 19 of an arm 20 of the frame 21, which is connected to the windmill frame as shown at 22 and disposed stationary. This frame 21 is constituted as a 80 guide frame owing to the provision of the recesses or notches 23, in which the rack frame is guided, there being metallic straps 24 for holding the rack bars 5 and 6 in said guide recesses.

The pinion 14 is mounted upon a pin 25, which is carried by the U-shaped bracket 26, which is bolted at 27 to the frame 21. This frame 21 comprises the upper and lower bars 28 and 29 bolted at 30 to the end bars 31 and 32. The pump rod 33 has teeth 34 which mesh with the teeth of the pinion 34'. The teeth of the pump rod are held in mesh with the teeth of the pinion 34', by means of the stout coil spring 35, which is interposed between one end of the frame 21 and the guide member 37, in which the pump rod is guided. 100

The windmill rod receives its motion in the usual manner, and in turn imparts a reciprocating motion to the rack frame, thereby operating the gear rims 12 and 16, and owing to the provision of the inner rim 16 meshing with the teeth of the pinion 14, which operates the pinion 34' (which is larger or substantially twice the size of the pinion 14) a faster movement is imparted to the pump rod, which engages or meshes 105 with the teeth of the pinion 34'.

The rack frame is made adjustable in or-

der to accommodate gears of different sizes, so as to change the movement of the pump rod.

The invention having been set forth, what is claimed as new and useful is:—

In combination, a stationary guide frame having a U-shaped bracket and provided with a bearing arm having a stub pin, larger and smaller concentrically arranged gears rotating together and mounted upon the stub pin of the bearing arm, a reciprocating rack frame having a set of teeth meshing with the larger gear, a pinion mounted in said U-shaped bracket and meshing with the teeth of the smaller gear, one

end of the rack frame having connections with an operating member, a member to be operated having teeth, a second pinion rotatable with the first pinion and meshing with the teeth of said member to be operated, and means whereby said rack frame may be adjusted to accommodate different size gearings. 20

In testimony whereof I have signed my name to this specification in the presence of two subscribing witnesses. 25

GEORGE A. KLEINOW.
